CONDUCTOR-TAPPING DEVICE

Ralph R. Pittman and Carroll H. Walsh, Pine Bluff, Ark.

Application September 11, 1939, Serial No. 294,300

6 Claims. (Cl. 173—273)

This invention relates generally to clamps adapted for electrically connecting a tap wire to an energized conductor, such devices being often referred to as "hot line" clamps.

Among the objects of the present invention may be noted (1) the provision of means for attaching and electrically connecting a clamp to a conductor, together with means for connecting and disconnecting a tap wire respectively to and from the clamp, such an arrangement assuring that the conductor to which the clamp is attached will be unaffected by any arcing which may attend the connection or disconnection of the tap wire; (2) the provision of a clamp which is attached to the conductor through resilient engagement therewith, so that a weight which is rigidly attached to the conductor is avoided, for the purpose of preventing embrittlement of the conductor at the point of attachment of the clamp; (3) and the provision of means for initially connecting the tap wire and subsequently disconnecting the tap wire in response to a predetermined downward movement of a contact member to which the tap wire is secured.

These and other objects will appear as the description proceeds, and the scope of the invention will be set forth in the appended claims.

In the drawing, Fig. 1 is a side elevational view of the invention; Fig. 2 is a front elevational view, shown partly in section.

Referring in detail to the drawing, the conductor-clamp 10 is preferably formed of a single piece of an inherently resilient conductor, such as a bronze wire, or a steel wire covered by a layer of copper. The clamp 10 consists broadly of two portions, an upper conductor-clamping portion, and a lower contact-engaging portion.

The upper conductor-clamping portion originates at the respective ends of the single wire forming the clamp, which are formed together by the copper sleeve 20. From the latter, the resilient wire extends upwardly in the form of the loops 12 and 26, above the conductor 25, to provide a coil which continually urges the portions 14 and 13 against the conductor 25, positioned therebetween, and in this manner the device is resiliently attached to the conductor to be tapped. The loops 12 and 26 also provide an eye into which a manipulating tool may be inserted, for the purpose of placing the clamp on the conductor by means of an insulated tool.

The lower contact-engaging portion of the clamp 10 is formed by two spaced portions of the wire which extend below the conductor 25 initially in spaced relation, the portions 15 and 16

bending first away from one another, and then toward one another, to provide an opening through which the contact member 11 may enter between the juxtaposed spaced portions 17 and 18. The lower end of the contact-engaging portion is formed into a loop 19, to provide an exit for the contact member 11; also to provide an opening into which a manipulating tool may be inserted to pull the clamp 10 into clamping engagement with the conductor 25.

The contact member 11 includes a metal contactor 21, of suitable dimensions for entering the opening formed by the outwardly bent portions 15 and 16 of the clamp, for frictionally engaging the adjacent and opposed surfaces of the contact-engaging portions 17 and 18, and for slidably moving downwardly between the latter portions to the loop 19, the latter being somewhat larger than the contactor 21 to permit easy release of the contact member from the clamp. The contact member is provided with a vertically extending aperture for receiving a tap wire 23, and a screw 24 threadedly engages an opening in registry with the tap wire opening, to mechanically and electrically connect the tap wire 23 to the contact member 11. A manipulating eye 22 is integrally formed with the contactor 21, for ease in handling the contact member and connected tap wire.

The procedure for applying and utilizing the conductor-tapping device will normally consist in first setting the clamp 10 on the conductor 25, by means of a suitable insulated tool in cooperation with the upper loops 12 and 26. The tool is then removed from the loops 12 and 26, inserted through the lower loop 19, and the clamp 10 pulled downward until it firmly grips the conductor 25 between the portions 13 and 14. The clamp is now in position to receive the contact member 11, to which the tap wire 23 has been previously attached. The insulated tool is now inserted through the eye 22, and the contact-member pulled downwardly through the opening formed by the outwardly bent portions 15 and 16 and into frictional and resilient engagement with the juxtaposed spaced portions 17 and 18. This is the normal connected position of the conductor-tapping device. Should it be desired to electrically disconnect the tap wire 23 from the conductor 25, the manipulating tool may again be inserted through the eye 22, and the contact member 11 again pulled downwardly through the juxtaposed portions 17 and 18, until the contactor 21 is released by passing into the opening of the loop 19, from which it may be removed.

It will be apparent that the tap wire 23 may be connected and disconnected at will from the conductor 25 without removing the clamp 10 from the latter, thus preventing any possible damage to the conductor from whatever burning or arcing may attend the connection and disconnection of the tap wire. It is also apparent that the weight due to the contact member 11, and the tap wire 23, is resiliently rather than rigidly supported from the conductor 25, so as to prevent damage to the latter in the event of conductor vibration due to wind or other causes.

From the above description, it may be seen that we provide a simple, effective, and easily 15 and safely manipulated conductor-tapping device, suitable for use in connecting and disconnecting tap wires respectively to and from conductors energized at a high voltage.

It will be understood that the drawing and 20 description herein are intended as illustrative rather than limiting, also that various modifications of our invention may be made without departing from the principles of the invention, and our invention is to be limited only as is necessitated by the prior art and the appended claims.

We claim as our invention:

1. A conductor-tapping device comprising a clamp having clamping means for attaching the clamp to a conductor, a detachable contact member associated with and slidably movable along said clamp, means for securing a tap wire to said contact member, and means responsive to a predetermined downward movement of said contact member with respect to said clamp for initially connecting said tap wire to said clamp and subsequently disconnecting said tap wire from said clamp.

2. A conductor-tapping device comprising, a clamp having a portion arranged to receive and 40 clamp a conductor and a contact-engaging portion extending downwardly from said conductor, a contact member associated with and slidably movable along said contact-engaging portion, means for electrically connecting a tap wire to said contact member, and means responsive to an initial predetermined downward movement of said contact member for attaching the latter to said contact-engaging portion and to a subsequent predetermined downward movement of 45 said contact member for detaching the latter from said contact-engaging portion.

3. A conductor-tapping device comprising, a clamp having an upper portion arranged to receive and clamp the conductor and contact-engaging portions extending downwardly below 50 said conductor, and a contact member associated with and slidably movable between said contact-engaging portions in frictional engagement therewith, said contact member being arranged to en-

ter the contact-engaging portions of said clamp in response to a predetermined movement thereof in a downward direction, and to be removably attached thereto by resilient engagement of the contact-engaging portions with the contact member.

4. A conductor-tapping device comprising a clamp having a portion arranged to receive and clamp a conductor and contact-engaging portions extending downwardly from said conductor, 10 and a contact member adapted to be secured to a tap wire, said contact member being arranged to enter between the contact-engaging portions of said clamp in response to a predetermined downward movement thereof, and to be removably attached thereto by resilient engagement of the contact-engaging portions with the contact member, and to be detached from said clamp in response to a predetermined downward movement which is in addition to said predetermined 20 movement.

5. A conductor-tapping device comprising a clamp formed of a single piece of inherently resilient wire, said clamp having a portion arranged to receive and clamp a conductor and 25 downwardly extending portions including a pair of downwardly extending spaced wire portions joined at their lower end, a contact member, means for securing a tap wire to said contact member, said contact member being arranged to bridge the space between and frictionally engage said spaced wire portions, the lower end portions of said spaced wire portions diverging above the juncture at the lowermost ends so as to release said contact member from frictional engagement in response to a predetermined downward movement.

6. A conductor-tapping device comprising a clamp formed of a single piece of inherently resilient wire, said clamp having an upper portion 40 adapted to grip a conductor and to be attached to the conductor thereby and a lower portion including a pair of downwardly extending spaced wire portions, said wire portions being positioned below said conductor and being formed to provide spaced juxtaposed portions positioned between upper and lower relatively diverging portions and being joined at their lower ends, a contact member, means for securing a tap wire to said contact member, said contact member being constructed and arranged, in response to a predetermined downward movement, to enter between the upper diverging portions, pass in frictional engagement between and through the juxtaposed portions, and to exit between the lower 45 diverging portions.
